UNITED STATES PATENT OFFICE.

JACOB B. BEAM, OF PUNXSUTAWNEY, PENNSYLVANIA.

AUTOMOBILE RADIATOR.

1,412,332.

Specification of Letters Patent. Patented Apr. 11, 1922.

Application filed July 30, 1917. Serial No. 183,553.

To all whom it may concern:

Be it known that I, JACOB B. BEAM, a citizen of the United States, residing at Punxsutawney, in the county of Jefferson and State 5 of Pennsylvania, have invented certain new and useful Improvements in Automobile Radiators, of which the following is a specification.

This invention relates to radiators for use 10 in connection with motor vehicles for the purpose of cooling the water which circulates in the cylinders of the engine and is an improvement on Patents #1,019,122, #1,026,895, #1,026,896, granted to me 15 March 5, 1912, and May 21, 1912, respectively.

The primary object of the invention is to provide a radiator casing stamped from sheet metal, in which the casing is utilized for the 20 circulation of water, the said casing containing upper and lower water chambers and independent tube sections communicating with said water chambers to provide a water circulation, the casing also being provided 25 with a front finishing bead, obviating the necessity of adding an additional finishing casing, thereby simplifying and improving the construction of the radiator and reducing the cost of maintenance.

Another object of the invention is to provide means whereby the independent tube sections may be inserted or removed from the rear of the casing, the radiator being susceptible of use with one or more of the independent tube sections removed, provision being made for closing the opening by which the water chambers establish communication with the tube sections.

The invention further consists of a novel 40 manner of forming and assembling the different parts of the radiator casing to provide water chambers therein and to provide for the convenient connection of the headers of the independent tube sections, some of 45 these headers being inserted and connected from the rear of the casing, while in one form of the invention the headers are secured in position by the assembling of the lower water chamber with the remainder of 50 the casing.

With the above and other objects in view, the invention consists of the following novel combination and arrangement of parts, hereinafter more fully described and illustrated 55 in the accompanying drawings, in which—

Figure 1 is a sectional elevation of one

form of radiator casing, most of the tube sections being removed;

Figure 2 is a vertical sectional view of the same on the line 2—2 of Figure 1; 60

Figure 3 is a view similar to Figure 1 of a casing formed with a V-shaped front face, such as is employed on some makes of motor vehicles;

Figure 4 is a sectional view on the line 65 4—4 of Figure 3;

Figure 5 is a horizontal sectional view on the line 5—5 of Figure 3;

Figure 6 is an enlarged fragmentary section of the connection between the upper 70 water chamber and the upper header of one of the independent tube sections, of the construction shown in Figures 1 and 2;

Figure 7 is a detail sectional view on the line 7—7 of Figure 6; 75

Figure 8 is a detail perspective view of one of the attaching lugs;

Figure 9 is a perspective view of the upper portion of one of the independent tube sections shown in Figures 3, 4 and 5; 80

Figure 10 is a view similar to Figure 6, but illustrating a different form of connection between the upper water chamber and upper header;

Figure 11 is a sectional elevation of a 85 modified form of casing;

Figure 12 is a section on the line 12—12 of Figure 11;

Figure 13 is a perspective view of a plate 90 for forming the upper water chamber;

Figure 14 is a similar view of the plate for forming the lower water chamber, both being of the form employed in Figures 1 and 2;

Figure 15 is an enlarged fragmentary sectional view of the connection between the lower water chamber and the lower header 95 of one of the independent tube sections shown in Figures 11 and 12;

Figure 16 is a fragmentary perspective 100 view of the upper end of one of the independent tube sections shown in Figures 11 and 12; and

Figure 17 is an enlarged sectional view on the line 17—17 of Figure 1. 105

In the usual construction of radiators, the radiator proper is ordinarily made of a single casting, which contains the upper and lower water headers or chambers connected together by the water circulating tubes. In 110 this form of radiator it is necessary to make the casting of considerable thickness in or-

der to secure strength and to prevent damage to the casting when the core which forms the space occupied by the water circulating tubes is removed. In order to present a neat and attractive appearance it is necessary to use in connection with this casting a cover or casing, thereby adding to the cost of manufacture and increasing the amount of material necessary to construct a radiator.

10 In order to overcome these and other disadvantages, the present invention contemplates the provision of a casing stamped from sheet metal, in which there is formed upper and lower water chambers, connected together by independent tube sections or units, the novel manner of forming the casing, simplifying its construction and materially reducing the cost of manufacture. As shown in the accompanying drawings, reference being had to Figures 1 and 2, there is provided a casing in which the front 10, sides 11, top 12 and bottom 13 are stamped from a single piece of sheet metal and shaped to provide a finishing bead 13' around the opening 14, which is provided with water circulating tubes.

15 Formed in the upper part of the casing is a water chamber 14^a, this chamber being formed by inserting within the upper end 30 of the casing just described a sheet metal plate 15, illustrated in Figure 13. This plate is shaped to provide a rear wall 16 of the casing and a bottom wall 17, the latter being inclined as shown to permit of the ready insertion and removal of the independent tube sections to be later described.

20 The plate 15 is brazed or otherwise secured within the casing and forms an absolutely water tight chamber. The plate 15 is formed with an inset portion 18, the vertical wall 19 of which is provided with a plurality of spaced openings 20, these openings being formed with a concentrically arranged seat 21, which is shown in Figure 6 of the drawings.

25 The casing is further provided with a lower water chamber 22, which is formed by a plate 23, stamped from sheet metal, this plate being also provided with an inclined upper wall 24 for a purpose hereinafter apparent. The rear wall of the casing 23 is provided with a plurality of spaced openings 25, which are arranged in vertical alignment with the openings 20 and like these latter openings are formed with concentrically arranged seats 26, this construction being best illustrated in Figure 17.

30 The upper water chamber is provided with a water inlet 27, and the lower chamber with an outlet 28, for connection with the ordinary water circulating system of an engine.

35 Communication is established between the upper and lower water chambers through the medium of water tubes 29, which are similar in construction to the tubes shown

and described in the above mentioned patents. These tubes are arranged in independent tube sections, each of which is provided with an upper water header 30 and a lower water header 31, the former being best 70 illustrated in Figure 6 of the drawings. This upper water header 30 is stamped from sheet metal and is provided with an open bottom, beneath which is secured a plate 32. This plate is formed upon each of its side 75 edges with a flange 33, which is adapted to be engaged with the side and end walls of the header 30. The plate is further provided with inwardly projecting spaced fingers 34, which provide notches 35, the latter 80 being adapted to receive the upper ends of the tubes 29. As in my former patents, these tubes are provided with transversely arranged horizontal projections or bosses 36, the topmost boss acting as a stop to limit the 85 entrance of the upper portion of the tubes 29 into the plate. The headers 31 are provided with plates 37, which are similar in construction to the plates 32 and are adapted to close the upper ends of the said headers. 90 The lower ends of the tubes 29 are inserted in the notches formed between the fingers of the plates 37, the lowermost boss of the tubes acting as a stop after the manner of the upper boss previously mentioned.

95 When these headers and tubes have been assembled, they are dipped so as to securely hold the parts together, the transverse bosses of the tubes abutting and effectually closing the opening in the plates 32 and 37, so that 100 an absolutely water tight joint is obtained.

Both the upper and lower headers are formed with spaced openings 38 and 39 respectively, around which are arranged outwardly projecting flanges 40 and 41, these 105 flanges being provided with inset portions forming shoulders 42 and 43, between which and the seats provided around the openings in the upper and lower water chambers are positioned gaskets 44. These gaskets are 110 L-shaped in cross-section and form a double seal at the points indicated by the reference numerals 45 and 46, so that an interlocking joint is provided between the water chambers and headers and any liability of leakage thereby prevented.

115 In the assembling of the parts just described, the independent tube sections are positioned so that their projecting flanges will extend within the seats on the upper 120 and lower water chambers and the independent tube sections are held in this position by means of screws 47 adapted to engage threaded openings 48 in the lower water chamber and similar openings 49 in the 125 upper water chamber, these screws carrying spanners 50, which bridge the space and engage the adjacent edges of the headers.

130 In order to secure the radiator in position upon a vehicle, there are provided at

taching lugs 51, each of which is stamped from a single piece of metal and folded to provide a flange 52, having registering openings 53. The end of the plate from which the lug is formed is bent to extend in opposite directions to provide flanges 54, which may be brazed or otherwise secured to the casing. There is further provided upon this attaching lug an integral front wall 10 55, one end of which is curved as shown at 56 to conform to the bottom edge of the radiator casing.

The construction shown in Figures 3 and 4 of the drawings is similar in all respects to that just described, except that the front face 57 of the casing is formed in an outwardly projecting point or V-shaped after the manner of radiators employed on some types of motor vehicles. To accomplish this, 20 it is necessary to extend the inset portion 18' a greater distance, and as the vertical wall of this portion is arranged at an angle as shown at 58 in Figures 4 and 10, the seats 59 which surround the openings 60 are arranged at an angle therein. This is done in order that the independent tube sections 25 may be positioned in the same manner as the sections in the form just described.

In the form shown in Figures 4 and 10, 30 the flanges 61 which surround the openings 62 of the water headers 63 of the independent tube sections are so disposed as to permit of the engagement of the flanges within the seats 59. The screws 64, by means of 35 which the headers are held in engagement with the water headers are received within threaded openings 65, these openings being disposed in alignment with the seats and flanges 59 and 61.

40 In the form of the invention shown in Figures 11 and 12, the casing is formed by stamping the front wall 66, the top wall 67 and side wall 68 from a single piece of sheet metal, the upper water chamber 69 being formed by securing the plate 70 45 stamped in a suitable form and secured after the manner of the plate 15, to provide the rear and bottom walls for the chamber 69.

The lower water chamber has its front 50 wall 71 formed separately from the upper water chamber, in this respect differing from the construction illustrated in Figures 1 and 2. This lower water chamber 72 is formed from sheet metal, stamped to provide a lower 55 wall 73, a rear wall 74 and an upper wall 75.

The water tubes 29 are arranged in independent tube sections, as described in connection with Figures 1 and 2 and like the construction shown in these figures are provided with upper water headers 76 and lower 60 water headers 77, the difference being that the openings by which communication is established between the upper and lower water chambers, are formed in the bottom 65 and top walls of the water chambers and

the top and bottom walls of the headers, the same method being utilized to insure a water tight joint in the form previously described.

In the assembling of the last form of 70 casing, the independent tube sections are connected with the top water header and the bottom chamber adjusted upon these tube sections, this chamber being held in position through the medium of screws 78 75 provided at each end of the bottom water chamber, these screws passing through a metal block 79 positioned at each end of the lower water chamber and engaging the block 80 brazed to each of the side walls of 80 the casing, this last mentioned block being formed with an offset 81 to provide attaching flanges for the radiator.

As will be seen from the foregoing description and the accompanying drawings, 85 each of the independent tube sections is removable and the radiator may be used after the removal of one or more of these sections, the openings provided in the water chambers being closed by means of a block, 90 in the form of a gasket 82, which is positioned upon the shank of a T-bolt 83. Also positioned upon the shank of the bolt is a disk 84 and a clamping nut 85. By reference to Figure 17 it will be seen that the 95 bolt 83 may have its head inserted through any one of the openings in the water chambers and the gasket 82 positioned against the flange, the gasket being securely held in such position by adjusting the nut 85. 100

It is believed that from the foregoing description when taken in connection with the accompanying drawings, the construction and advantages of the invention will be apparent. The right is reserved to make 105 such changes in the form and proportion thereof as will fall within the scope of the claims hereto appended.

Having described the invention, what is claimed is:

1. A radiator for motor vehicles embodying a casing stamped from sheet metal and formed to provide three walls of both an upper and a lower water chamber, sheet metal plates stamped to form the remaining wall of each of said chambers, seats formed in said plates, said seats including inwardly extending tubular members and inwardly extending annular flanges surrounding the inner ends of said members, independent tube sections connecting said water chambers, said sections each being provided with a header having a flanged opening therein adapted to be positioned within one of the seats of the water chamber, an inwardly offset restricted extension provided around the flanged openings of the headers and spaced from the plate flanges to provide gasket spaces, a gasket positioned within each of said spaces and means for connect- 110 115 120 125 130

ing the independent tube sections to the water chambers to removably hold them in position.

2. A radiator for motor vehicles embodying a casing stamped from a single piece of sheet metal to form three walls of an upper and a lower water chamber and connecting side walls, sheet metal plates stamped to form the remaining walls of each of said chambers and tubes connecting each of said chambers to provide a water circulation therebetween.

3. A radiator for motor vehicles embodying a casing stamped from sheet metal to provide an upper and a lower water chamber having aligned openings in the rear walls thereof, forwardly and upwardly inclined opposed walls for said sections, independent tube sections each provided with upper and lower headers, inclined top and bottom walls for said headers for contact with the inclined walls of the water cham-

bers, said headers having an opening therein adapted to be positioned so as to establish communication between said chambers and 25 headers and means for removably securing the tube sections to the water chambers to provide a water tight joint.

4. A radiator for motor vehicles embodying a casing stamped from sheet metal, 30 upper and lower water chambers formed by said casing and water circulating tubes communicating with said chambers tapered contact walls between the tubes and headers and a telescopic joint between the tubes and 35 chambers and disposed in substantially the same direction as the tapered contact walls, whereby a water tight joint is provided between the water chambers and tubes.

In testimony whereof I affix my signature. 40
JACOB B. BEAM.
